(57) **CLAIM**

The ornamental design for a card reverse surface, as shown and described.

DESCRIPTION

The FIGURE is a view of the card reverse surface showing my new design.

The broken line showing portions of the card reverse surface and the dash-dot-dash line showing no specific length and width of the card reverse surface are included for the purpose of illustrating environmental structure and form no part of the claimed design.

The text and the asterisk following the third solid line in the upper left hand corner of the FIGURE and the barcode in the lower right hand corner of the FIGURE are illustrated in broken lines and form no part of the claimed design.
